US0D1012916S

(12) **United States Design Patent** (10) **Patent No.:** **US D1,012,916 S**
(45) **Date of Patent:** **** Jan. 30, 2024**

(54) **PHONE CASE**

(71) Applicant: **Shenzhen Ximeisi Technology Co., Ltd.**, Shenzhen (CN)

(72) Inventor: **Kai Zou**, Fuzhou (CN)

(73) Assignee: **Shenzhen Ximeisi Technology Co., Ltd.**, Shenzhen (CN)

(**) Term: **15 Years**

(21) Appl. No.: **29/886,661**

(22) Filed: **Mar. 10, 2023**

(51) LOC (14) Cl. **14-03**

(52) U.S. Cl.

USPC **D14/250**

(58) **Field of Classification Search**

CLAIM

The ornamental design for a phone case, as shown and described.

DESCRIPTION

FIG. 1 is a front perspective view of a phone case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear, right-side, and top perspective view thereof showing the rear compartment in an open state; and, FIG. 10 is a rear, left-side, and bottom perspective view thereof showing the rear compartment in an open state.

1 Claim, 10 Drawing Sheets
